FUEL FEEDING DEVICE FOR LOCOMOTIVES
OR THE LIKEEdgar M. Wilcox, Chicago, Ill., and Alexander M.
Stockwell, Elkhart, Ind.

Application June 22, 1935, Serial No. 27,996

6 Claims. (Cl. 198—15)

The present invention relates to fuel feeding devices, and more in particular to fuel feeding devices for locomotive tenders.

Among the objects of the present invention is to provide a novel fuel feeding device adapted to be installed in locomotive tenders.

Locomotive tenders, as is well-known, serve as fuel storage means and are connected immediately to the rear of the locomotives whereby the fuel may be fed to the locomotive boilers, as desired, during a run between various points. In the more advanced types of locomotive tenders, the fuel is not conveyed to the locomotive boilers manually, but on the other hand, by stokers which feed the fuel, such as coal or the like, forwardly to the locomotive boilers. These locomotive tenders are provided with a rear slope sheet, the intended function of which is to prevent accumulation of coal at the rear of the bin and to provide a downwardly inclined surface over which the last remaining portions of the coal supply will gradually and progressively move forward to be picked up and moved by the conveyor to the locomotive boiler. It has been found, however, that such rear slope sheets retain a substantial quantity of the coal banked against them, and this coal, which might otherwise be used for fuel purposes to increase the length of run for the locomotive, remains on the slope sheet and upon refueling continues to remain as a dead weight and is never consumed as fuel. The coal is therefore transported from place to place, which increases operating costs.

It is therefore an object of the present invention to provide novel means adapted to remove the fuel banked against the rear slope sheets of locomotive tenders whereby this fuel may be used to increase the distance that the locomotives may operate without refueling.

More particularly, the present invention has as an object the idea of providing a novel fuel pushing means which may be used in conjunction with a stoker to feed the fuel forwardly to the locomotive boiler.

Still another object of the present invention is to provide a novel fuel pushing means adapted to progressively move in either of two directions and which is operated with the stoker from a common source of power.

Another object within the purview of the present invention is to provide such a novel fuel pushing means above the rear slope sheet of the locomotive tender which is movable thereover as desired from a source of power used for driv-

ing the stoker mechanism of the locomotive tender.

Still a further object of the present invention is to provide a novel driving means for the fuel pusher which is controlled automatically by the pusher.

The present invention also contemplates the idea of providing a common drive for a stoker and fuel pusher in a locomotive tender, the drive for the pusher being manually controlled from the front of the tender and disconnected automatically by the fuel pusher.

Other objects, features, capabilities and advantages are comprehended by the invention, as will later appear and as are inherently possessed thereby.

Referring to the drawings:

Figure 1 is a fragmentary top plan view of a locomotive tender incorporating the fuel feeding device made in accordance with the present invention;

Figure 2 is a fragmentary view in vertical cross-section taken in the plane represented by line 2—2 of Figure 1 of the drawings; and

Figure 3 is a fragmentary view in cross-section taken in a plane represented by line 3—3 of Figure 1 of the drawings.

Referring now more in detail to the drawings, an embodiment of a fuel feeding device made in accordance with the present invention is shown as comprising a stoker 2 and a fuel pusher 4, the same being incorporated in a locomotive tender 6. As is well-known, the locomotive tender 6 serves as a fuel bin immediately to the rear of the locomotive and includes a floor 8 and a rear slope sheet 10 which is provided with angle irons 11 and 13 for guiding the fuel pusher during its movement over the surface of the slope sheet. The floor 8 is formed in part by the stationary floor pieces 12 and 14 and disposed therebetween are removable floor pieces 16, 18, etc., these floor pieces being disposed immediately above a screw type conveyor 19 operable within a fuel conduit 20 in communication with the fuel bin. This screw type conveyor is adapted to advance the fuel forwardly to the locomotive boiler, as desired. Initially when the tender is filled with coal, the most forwardly disposed floor piece is removed in order that the fuel may drop by gravity into the fuel conduit where it is engaged by the screw type conveyor to be fed to the locomotive boiler. As the coal is consumed, the floor pieces such as 16 and 18 are progressively removed in order that sufficient coal may be fed to the conveyor without manual handling.

Such a conveyor as above described may be operated by an auxiliary stoker engine 21 disposed in the locomotive tender, as shown, or in the locomotive if desired, this engine being suitably coupled to and driving a shaft 22 extending rearwardly from the front of the tender, this shaft being coupled through the universal joint 24 to a shaft 26 of a gear housing 28, which gear housing includes suitable gears for rotating the conveyor.

Although the rear slope sheet of the locomotive tender is inclined to permit forward movement of fuel, such as coal or the like, nevertheless coal which is banked against and upon the same does not move forwardly to a position where it is picked up by the conveyor and fed to the locomotive boiler without manual handling. The present invention, however, contemplates the use of the pusher 4 for moving the coal forwardly whereby the same is picked up by the conveyor to be conveyed forwardly to the locomotive boiler. This pusher means comprises a pusher member 30 of the general shape disclosed in Figure 1 of the drawings, the same including a central body portion 32 and laterally extending arms 34 and 36. The central body portion and arms are provided with the forward pushing surface 38 disposed substantially normal to the plane of the rear slope sheet 10 for pushing the coal forwardly and downwardly. These parts of the pusher member are also formed with the rearwardly disposed knife edges 40 and 42 whereby the pusher may be moved upwardly through the coal lodged against the slope sheet, as will be described more in detail hereinafter.

The present invention contemplates the idea of operating the pusher member by the driving means which operates the stoker. As disclosed in the drawings, the pusher driving means includes a shaft 48 substantially in alignment with shaft 26 and driven thereby. If desired, shaft 48 may be integral with shaft 26 or secured to a gear in the gear box 28 which is driven by shaft 26 and is mounted at its rear end in the bearing 50 secured to the frame member 52 of the tender. Mounted upon the shaft 48 is a clutch member 54 having a plurality of teeth disposed on each end thereof, this clutch member being splined to the shaft whereby the same is rotated thereby and may be moved axially with respect thereto. Rotatably mounted upon the shaft 48 and adjacent but in spaced relation to the ends of the clutch member 54 are bevel gears 56 and 58, each of which has a hub provided with projecting teeth engageable by the clutch member 54.

Meshing with the gears 56 and 58 is a bevel gear 60 mounted upon the shaft 62 which is journaled for rotation in the bracket 66 secured to the frame member 52 of the tender. Secured to the shaft 62 adjacent the top and bottom of the bracket 66 are thrust collars 64, and mounted upon the upper end of shaft 62 is a bevel gear 68 meshing with another bevel gear 70, which bevel gear is fixed to a shaft 72 extending longitudinally below the slope sheet 10. This shaft 72 is mounted for rotation at its lower end adjacent the junction or intersection of the slope sheet 10 with the floor 8, in a bearing 74 between which and the gear 70 is a thrust collar 71. At its upper end the shaft 72 has a universal connection 76 for connecting the same to a stub shaft 78, which stub shaft is journaled in the bearing 80 secured to the lower face of the slope sheet.

Mounted upon the upper end of the stub shaft 78 is a bevel gear 82 meshing with bevel gear 84 mounted upon shaft 86 which is journaled in a bracket 88 secured to the underside of the slope sheet 10. This shaft 88 has a spur gear 90 secured to an end thereof, which is adapted to extend through an opening 92 formed adjacent the upper end of the slope sheet 10 and mesh with a rack 94 disposed within the housing 96 secured to the slope sheet adjacent the slot or opening 92 thereof. The rack 94 has its lower end pivotally connected as at 98 to the central body portion of the pusher member.

As disclosed in Figure 2 of the drawings, the clutch member 54 is disposed in its neutral position out of engagement with teeth on the gears 56 and 58, and when it is desired to move the pusher member upwardly from its lowermost position, the clutch member 54 may be moved into engagement with the gear 58 whereby the drive 20 for the pusher member is through shaft 48, gears 58, 60, 68 and 70, for driving the shaft 72 and its associated mechanism. Movement of the clutch member 54 is effected by a rod 100 connected at one end to a collar 102 embracing the clutch member 54 and at its other end to the lower end of operating handle 104 pivotally mounted as at 106 in a bracket 108 secured to a wall of the locomotive tender adjacent its forward end. Upon interengagement of clutch member 54 and gear 58, pusher member will move upwardly whereby the knife edges 40 and 42 thereof cut through the coal to loosen the same, whereupon this loosened coal is more easily moved downwardly over the surface of the slope sheet 35 to the conveyor upon downward movement of the pusher. It is of course understood that after the pusher member has reached its upper limit, the clutch member 54 and gear 58 are disengaged whereby the pusher member remains stationary. When it is desired to move the pusher member downwardly, handle 104 may be operated to effect an engagement between clutch member 54 and gear 56 whereby the pusher member is moved in a reverse direction. Although I 45 have described the pusher member as moving within certain limits over the slope sheet upon engagement of the clutch member 54 with gears 56 and 58, it is to be understood that the movement of the pusher member either upwardly or 50 downwardly may be controlled by manual operation of the handle or lever 104.

The present invention also provides means for moving the clutch member 54 into a neutral position when the pusher member has reached either its upper or lower limit of travel. Such means includes levers 110 and 112 pivotally mounted, respectively, on brackets 114 and 116 secured to and depending from the underside of the slope sheet 10. These levers extend upwardly through suitable slots 118 and 120, respectively, provided in the slope sheet and have their upper ends disposed in the path of movement of the pusher member. The lower ends of these levers are pivotally connected to the 60 rod 122 which has its lower end pivotally connected to one arm of a bell crank lever 124 which is pivotally mounted in a bracket 126 secured to the floor 8. The other arm of the bell crank lever is pivotally connected to a rod 128 disposed substantially parallel to rod 100 and has its other end connected to the operating handle 104 in spaced relation but adjacent the connection of rod 100 thereto.

As disclosed in Figure 2 of the drawings, the 75

pusher member is disclosed as having reached its lower limit of travel. As the pusher member approaches its lower limit of travel, lever 110 is engaged thereby whereby rod 122 is moved upwardly to move rod 128 to the right through the bell crank lever 124. This movement to the right of rod 128 causes a similar movement of rod 100 through operating handle 104 whereby a disengagement between clutch member 54 and gear 56 is effected. Inasmuch as clutch member 54 is in its neutral position, continued rotation of the stoker driving mechanism is ineffective to operate the pusher mechanism. When it is desired to move the pusher member upwardly, operating lever 104 is manually operated to effect an interengagement between clutch member 54 and gear 58, which engagement is maintained until lever arm 112 is engaged by the pusher member. Such an engagement causes movement of rod 128 from right to left through rod 122 and bell crank lever 124 and through rod 100 the clutch 54 is moved to the left into its neutral position.

It will therefore be clearly apparent that provision is made for continued operation of the stoker mechanism as desired without operation of the pusher mechanism. It is also to be understood that although the pusher mechanism in the present embodiment is disclosed as being operated through shaft 48 in alignment with shaft 22 from the auxiliary stoker engine, such pusher mechanism, if desired, may be operated by the shaft for the screw type conveyor. It will also be appreciated that the relative rate of speed of the conveyor and pusher member may be controlled, as desired, by the proper selection of gears in gear box 28 and driving the pusher from either the high or low side thereof, as well as by selecting proper gears in the pusher drive itself.

While we have herein described and upon the drawings shown an illustrative embodiment of the invention, it is to be understood that the invention is not limited thereto but may comprehend other constructions, arrangements of parts, details and features without departing from the spirit of the invention.

We claim:

1. In a stoker conveyor system for transferring fuel from a tender to a locomotive, the combination of a locomotive tender connected to said locomotive and having a fuel storage bin provided with a rear slope sheet, a stoker for transferring fuel from said bin to said locomotive, a reciprocating fuel pusher mounted for movement with respect to the surface of said slope sheet for transferring fuel disposed thereon toward said stoker, a stoker engine, a drive extending from said stoker engine, means connected to said drive for operating said stoker, means connected to said drive for operating said fuel pusher, clutch means in said last-named means for controlling said fuel pusher, and means operated by the operation of said fuel pusher operating means at the ends of the pusher stroke for controlling the operation of said clutch means for stopping the movement of said fuel pusher.

2. In a stoker conveyor system for transferring fuel from a tender to a locomotive, the combina-

tion of a locomotive, a locomotive tender connected to said locomotive and having a fuel storage bin provided with a rear slope sheet, a stoker for transferring fuel from said bin to said locomotive, a reciprocating fuel pusher mounted for movement over the surface of said slope sheet for transferring fuel disposed thereon toward said stoker, means for operating said stoker and said fuel pusher, said last-named means having clutch means for controlling said fuel pusher, and automatic means operated at the ends of the pusher stroke for controlling the operation of said clutch means for stopping the movement of said fuel pusher.

3. In a stoker conveyor system for transferring fuel from a tender to a locomotive, the combination of a locomotive tender connected to said locomotive and having a fuel storage bin provided with a rear slope sheet, a stoker for transferring fuel from said bin to said locomotive, a reciprocating fuel pusher mounted for movement over the surface of said slope sheet for transferring fuel disposed thereon toward said stoker, a stoker engine, means driven by said stoker engine for operating said stoker and said fuel pusher, said last-named means having clutch means for controlling said fuel pusher, and automatic means operated at the ends of the pusher stroke for controlling the operation of said clutch means for stopping the movement of said fuel pusher.

4. In a locomotive tender, the combination of a fuel storage bin provided with a rear slope sheet, a reciprocating fuel pusher mounted for movement with respect to the surface of said slope sheet for moving fuel away from said slope sheet, a stoker engine, means driven by said stoker engine for operating said fuel pusher, said means having clutch means for controlling said fuel pusher, and means operated by the operation of said fuel pusher operating means at the ends of the pusher stroke for controlling the operation of said clutch means for stopping the movement of said fuel pusher.

5. In a locomotive tender, the combination of a fuel storage bin provided with a rear slope sheet, a reciprocating fuel pusher mounted for movement over the surface of said slope sheet for moving fuel toward the forward end of said bin, means for operating said fuel pusher, said last-named means having clutch means for controlling said fuel pusher, and automatic means operated at the ends of the pusher stroke for controlling the operation of said clutch means for stopping the movement of said fuel pusher.

6. In a locomotive tender, the combination of a fuel storage bin provided with a rear slope sheet, a reciprocating fuel pusher mounted for movement with respect to the surface of said slope sheet for moving fuel away from said slope sheet, a stoker engine, means driven by said stoker engine for operating said fuel pusher, said means having clutch means for controlling said fuel pusher, and automatic means operated at the ends of the pusher stroke for controlling the operation of said clutch means for stopping the movement of said fuel pusher.

EDGAR M. WILCOX,
ALEXANDER M. STOCKWELL.
